United States Patent Office.

GEORGE A. HIGGINS, OF NEW YORK, N. Y.

Letters Patent No. 99,437, dated February 1, 1870.

IMPROVED CHAMBER-PAIL.

The Schedule referred to in these Letters Patent and making part of the same.

To all whom it may concern:

Be it known that I, GEORGE A. HIGGINS, of the city and State of New York, have invented and made a new and useful Improvement in Chamber-Pails; and the following is declared to be a correct description of the same.

Chamber-pails are usually made of sheet-metal, with a movable cover and bail, the water from portable basins and the contents of chambers being emptied into such chamber-pails, and these are generally carried to the privy or water-closet to be emptied.

In making use of chamber-pails in this manner, there are several inconveniences. The contents are apt to be spilled upon the seat as the pail is emptied; water has to be carried to rinse out the pail; and usually a cloth must be provided for wiping up whatever may spill upon the seat. Besides this, the smell arising from these chamber-pails while in use is disagreeable.

My invention is intended to remedy all the before-named difficulties, and consists in a chamber-pail and valve combined, so that the valve can be opened to allow the contents to be discharged from the bottom of the pail, after the same has been set upon the privy or water-closet seat, so as not to spill any water on said seat. I also make the cover of said pail hollow, to contain rinsing-water, that is allowed to run out when the cover is inverted, upon the pail. I also make the top flange of the pail of sufficient width to form a seat, so that said chamber-pail can be used as a portable night-convenience, and this flange is covered with India rubber, to make a more easy seat, and also to keep in smell, by forming a tight elastic seat for the cover of the pail.

In the drawing—

Figure 1 is a vertical section of the pail, as in a condition for transportation to the privy or water-closet, and

Figure 2 shows the top part of the pail with the cover inverted, to cause the water contained therein, to wash out the pail.

The pail, *a*, is made of any usual size or shape, and *b* represents the handle or bail.

In the bottom of the pail is an opening for discharging the contents, and a valve, *c*, to close that opening.

This valve, *c*, may be made in any desired manner. I prefer to have the same hinged, as at *d*, and make

use of an elastic face, on the under side of the pail, secured by metal ring, so that the valve *c* may close against this seat.

The latch, *f*, is fitted in the under part of the pail, to take a loop or catch, projecting from the valve, and hold the valve pressed firmly against the seat.

I prefer that the under side of the valve, and the skirt or rim of the pail, be in the same plane, so that the valve may rest upon the floor, and thereby be pressed to the seat.

At the top of the pail a metal flange, *g*, is made, and upon this there is an elastic surface, formed by expanding a cylindrical rubber ring around the edges of said flange, the contraction of the same holding the ring in place, and causing it to lie flat upon the top of the flange.

This elastic surface to the flange *g* makes the cover of the pail tight, and forms an easy seat, when the pail is used as a night-convenience.

The cover of the pail is formed as a water-vessel, *h*, having a flange, *i*, a supply-tube, and funnel *k*, and exit-holes *l*.

By this construction, the water is not liable to spill as the pail and cover are carried from one place to another, and when the cover is inverted, almost all the water is discharged from the holes *l* in jets, to wash out the inside of the pail.

I claim, as my invention—

1. A portable chamber-pail, with a discharge-opening in the bottom, in combination with a valve for closing the said opening, substantially as set forth.

2. The flange *g*, at the top of the chamber-pail, upon which a band of India rubber is applied, surrounding the exterior of such flange, and covering the top surface, as and for the purposes set forth.

3. The chamber-pail-cover, made as a hollow vessel, entirely closed at the bottom, and with an opening at the top, for receiving water for rinsing said pail, as set forth.

4. The water-vessel *h*, flange *i*, funnel and tube *k*, and exit-holes *l*, forming the cover of a chamber-pail, as and for the purposes specified.

Signed this 22d day of December, A. D. 1869.

GEORGE A. HIGGINS.
